FOUNDRY LADLE

Oscar L. Coffey, Harvey, Ill., assignor to Whiting Corporation, Harvey, Ill., a corporation of Illinois

Application December 17, 1934, Serial No. 757,852

4 Claims. (Cl. 22—81)

The present invention relates generally to foundry ladles. More particularly the invention relates to that type of ladle which is adapted to be transported to the flasks by a crane and then tilted to pour the molten metal therefrom.

The primary object of the invention is to provide a foundry ladle which is efficient in operation and has improved automatically operating brake means for locking the ladle against movement by the load while permitting it to be tilted or shifted by the operator.

Another object of the invention is to provide a foundry ladle which is generally of new and improved construction and may be manufactured at a low and reasonable cost.

Other objects of the invention and the various advantages and characteristics of the present ladle design will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Fig. 1 is a front elevation of a foundry ladle embodying the invention. Fig. 2 is an enlarged section on line 2—2 of Fig. 1. Fig. 3 is a section on line 3—3 of Fig. 2. Fig. 4 is a plan view of the ladle tilting means. Fig. 5 is a section on line 5—5 of Fig. 2. Fig. 6 is an enlarged section on line 6—6 of Fig. 5 showing the automatic brake device. Fig. 7 is an enlarged section on line 7—7 of Fig. 2. Figs. 8 and 9 are enlarged sections taken on line 8—8 of Fig. 7 respectively.

The ladle which forms the subject matter of the invention is adapted for use in a foundry in connection with the pouring of molten metal into flasks and comprises a pot *a* of any suitable construction. This pot is provided with coaxial trunnions *a'* on the sides thereof and is pivotally mounted in a bail *c* which is adapted to be suspended from a crane so that the ladle can be transported to the flasks or molds into which the molten metal is to be poured.

The ladle in addition to the pot and bail comprises mechanism for tilting the pot for metal pouring purposes. The mechanism comprises a gear *15* which is keyed to one of the trunnions *a'*; a worm *16* which engages and serves to drive the gear *15*; a shaft *17* which is fixed to rotate with the worm *16*; a helical gear *18* which is fixed

to the shaft *17*; a helical gear *19* which meshes with the gear *18*; a shaft *20* which is fixed to the gear *19*; an arm *21* which is fixed to the shaft *20*; a disk *22* which is provided with abutments *23* and *24* for engaging the arm *21* to shift it in opposite directions; a sleeve *25* which is fixed to the disk *22* and is journaled on an extension of the shaft *20*; and a handwheel *26* which is fixed to the sleeve *25*. The gear *15* and worm *16* are enclosed in a case *27* which is adapted to retain lubricant and is provided with a pair of oppositely facing lugs *28*. A lug *29* which is fixed to one of the depending arms of the bail *c* extends between the lugs *28* and coacts with the latter to secure the case *27* against rotation relatively to the bail. The shaft *17* is journaled in ball bearings *30* in the case *27*. The helical gears *18* and *19* are enclosed in a chamber in an extension *27a* of the gear case *27* and this extension is also adapted to contain lubricant. A removable head *31* is provided at the outer side of the extension *27a* to provide access to the gears *18*, *19*. The shaft *20* for the gear *19* is journaled in ball bearings *32* which are carried in the walls of extension *27a*. The top of the gear case *27* is provided with an opening through which a sufficient supply of lubricant may be poured into the gear case to submerge the lower portion of the gear *15*. This opening is normally closed by a screw plug *34*.

In a ladle of the type under consideration it has been found that the operation of the gearing in tilting the ladle does not result in sufficient lubrication of the worm *16* and the helical gears *18* and *19*, because the range of movement of the gear *15* in the operation of the ladle is not always sufficient to lift the lubricant to the worm and helical gears. To overcome this deficiency means is provided for forcing a portion of the lubricant from the lower portion of the gear case *27* and elevating it so it will be discharged onto or above the worm *16* and into the chamber in the case extension *27a* which contains helical gears *18* and *19*, whenever the pot *a* is tilted in either direction. This means comprises an oil pump *35* in a well at the bottom of the gear case *27*. This pump comprises a piston *36* which is pressed upwardly by a spring *37* and has its upper end *38* tapered as shown in Fig. 2. The tapered end of the piston rides on the periphery of the gear *15* with the result that the piston is reciprocated by the teeth whenever this gear is rotated in either direction. The piston *36* is slidably mounted in a cylinder *39*. Oil passes from the supply in the lower portion of the gear case *27* through a pipe *55*

40 and a duct 41 in a block 42 to a downwardly closing ball check valve 43 which permits oil to enter the cylinder 39 on the upward or suction stroke of the piston 36 and closes the duct on the downward or pressure stroke of the piston. On the down stroke of the piston the oil in the cylinder 39 is forced through a duct 44 in the block 42 and a pipe 45 which extends upwardly and terminates above the worm 16 at a suitable point 5 to discharge the oil onto the periphery of the worm. A pipe 46 leading from the pipe 45 discharges some of the oil from the pump into the chamber in the case extension 27^a which contains the helical gears 18 and 19. The lower 10 portion of the gear 19 is submerged in the oil in the lower portion of the extension 27^a and carries a portion of the oil to the gear 18. The branch pipe 46 extends through an opening 47 through which oil above a predetermined level in 15 the extension 27^a will flow back into the lower portion of the gear case 27. A ball check valve 48 is provided in the pipe 45 to prevent the back-flow of oil from the pipe 45 during the suction stroke of the piston 36. The case 27 is formed 20 with an integral well 27^b for the pump. Preferably the cylinder 39 is formed in a filling of babbitt or other suitable metal which is cast in the well 27^b around the block 42 and the lower 25 portions of the pipes 40 and 45. This constitutes 30 an economical method for forming the cylinder of the pump in the well of the gear case.

In operation, whenever the wheel 26 is turned to operate the gearing for tilting the pot *a* in either direction, the pump piston reciprocates 35 cause of the action of the teeth of the gear 15 on the tapered upper end 38 of the piston 36. The pump piston which on its upward stroke will suck oil through the pipe 40 into the cylinder 39 and during the down stroke force the oil through 40 the pipe 45 so it will be discharged onto the worm 16 and through the branch pipe 46 to the chamber in the extension 27^a of the gear case. As a result, the operation of the gearing for tilting 45 the pot in either direction will operate the oil pump and force the oil so it will be discharged onto the worm 16 to lubricate the engaging surfaces of said worm and the gear 15. The lower portion of the helical gear 19 rotates 50 in a bath of oil and carries the lubricant to the gear 18 and this is sufficient for efficiently lubricating the gear 18 because in ordinary use the gear 19 is completely rotated. This mechanism exemplifies force feed means operated by the 55 gearing for tilting the pot which elevates and conducts the oil to keep the gearing well lubricated at all times.

In order to lock the gearing and the pot against rotation, except through the handwheel 15, so that the pot will not be tilted by the load or pass 60 beyond the control of the operator automatic braking means is provided. This means comprises a brake shoe 49 with a brake lining 50 which is adapted to engage the inner periphery of a drum 51. The latter has a hub which is 65 screw-threaded at 52 into one side of the extension 27^a of the gear case 27 and is locked thereto by a screw 53. The shoe 49 is carried by a pair of rollers 54 and 55 and is disposed between the abutment lugs 23 and 24 on the disk 70 22. A spring 56 is applied between the arm 21 and the shoe and serves to hold the lining 50 of the shoe in a very light frictional contact with the inner periphery of drum 51. The roller 54 is adapted to be engaged by a cam surface 57 on 75 the arm 21 when the arm is shifted in one direc-

tion by the load through the gears 15, 16, 18, 19 so that one end portion of the shoe 49 will be jammed against the inner periphery of the drum 51 and prevent movement of the arm 21 and the gearing. When the load which applied to the 5 pot tends to move the gearing in the reverse direction an oppositely acting cam surface 58 on the arm 21 forces the roller 55 outwardly to jam the other end portion of the brake against the inner periphery of drum 51 and prevent the load 10 from rotating the gearing. When the handwheel 26 is rotated in one direction, the abutment lug 23 on the disk 22 will engage one end of the 15 brake shoe 49 and the arm 21 to shift conjointly the shoe and the arm without producing any 20 braking action between the shoe and the drum 51. When the handwheel 26 is rotated in the opposite direction, the abutment lug 24 on the disk 22 will engage the opposite end of the 25 brake shoe and the arm 21 and conjointly shift the 30 brake shoe and arm without braking action of the shoe against the drum 51. This exemplifies an automatic braking device for preventing rotation of the gearing by the load or pot so the 35 pot and gearing will remain in assigned positions. It will also prevent any overhauling of the 40 gearing by the load. This automatic braking is of 45 importance where the gearing is kept well lubricated.

The invention is not to be understood as restricted to the details set forth, since these may be modified within the scope of the appended 50 claims, without departing from the spirit and scope of the invention.

Having thus described the invention, what I 55 claim as new and desire to secure by Letters Patent is:

1. In a foundry ladle of the character described, the combination with a pot and suspension means whereby the pot is pivotally suspended, of mechanism for tilting the pot comprising a handwheel and gearing between said wheel and pot, a brake for the gearing, and means whereby the brake is automatically rendered operative when the load tends to move the 40 45 gearing and inoperative when the handwheel is rotated.

2. In a foundry ladle of the character described, the combination with a pot and suspension means whereby the pot is pivotally suspended, of gearing for tilting the pot, a handwheel for operating the gearing, a case enclosing the gearing, a brake drum fixed to the case, a brake shoe engageable with the drum, means for shifting the shoe with the handwheel when the handwheel is operated, and means between the 50 55 gearing and the shoe for rendering the shoe operative against the drum when the load is applied to shift the gearing.

3. In a foundry ladle of the character described, the combination with a pot and suspension means whereby the pot is pivotally suspended, of gearing for tilting the pot, a handwheel for operating the gearing, a case enclosing the gearing, a brake drum fixed to the case, a brake shoe engageable with the drum, means for shifting the shoe with the handwheel when the handwheel is operated, and an arm operatively connected to the gearing and provided with cam means for shifting the shoe against the drum 60 65 70 when the load tends to shift the gearing.

4. In a foundry ladle of the character described, the combination with a pot and suspension means whereby the pot is pivotally suspended, of gearing for tilting the pot, a hand- 75

wheel for operating the gearing, a case enclosing the gearing, a brake drum fixed to the case, abutments movable by the handwheel, a brake shoe engageable with the drum, and an arm provided with cam means for forcing the shoe against the drum, and connected to the gearing,

said arm and said shoe being engageable by the abutments when the handwheel is operated, said arm being movable relatively to the abutments to operate the shoe.

OSCAR L. COFFEY. 5
